Attorney.

UNITED STATES PATENT OFFICE.

LIONEL WILLIAM MACER, OF PILGRIMS REST, TRANSVAAL, SOUTH AFRICA.

RAIL-JOINT.

1,222,313.

Specification of Letters Patent. Patented Apr. 10, 1917.

Application filed June 23, 1915. Serial No. 35,763.

To all whom it may concern:

Be it known that I, LIONEL WILLIAM MACER, a subject of the King of Great Britain, residing at Pilgrims Rest, Trans-
vaal, Province of the Union of South Africa,
have invented certain new and useful Im-
provements in Rail-Joints, of which the fol-
lowing is a specification.

The present invention consists in im-
proved means for joining the ends of rail-
road and like rails, which means may also
be employed for supporting and securing the
rail between its ends. The device can be
fitted up more rapidly and with less labor
and cost than the usual fish plate joint. It
is especially applicable to light portable
railways.

The accompanying drawing shows the
invention applied as a rail joint; Figure I
being a perspective view and Fig. II a trans-
verse section taken through the meeting ends
of the rails.

The means comprises a sole plate or
sleeper 1 provided with members 3 which
extend upwardly and usually somewhat in-
wardly, forming between them a trough.
The bases 4 of the meeting ends of the rails
2 rest in the bottom of the trough, which is
just wide enough for them to pass freely
into it.

The locking means consists of a plain
plate 5 driven in between the underside of
the head 6 of the rail and the angle formed
between the upwardly directed members 3
of the sole plate and the base flange 4 of
the rail. By this means the rail and sole
plate are frictionally bound together.

In order to facilitate the insertion and
tight fitting of the locking plate, it is prefer-

able to taper the edges 7 very slightly, that 40
is to make the distance between said edges
7 rather less at the entering end of the
plate than at the other or driving end.

For a joint it is desirable to have a locking
plate 5 at each side of the rails as shown, 45
said plates being driven in from opposite
directions. Each plate binds its rail to the
sole plate which thus forms the connection
between the rails. The plates may if de-
sired be driven past and bridge the meeting 50
point of the rails, as shown, to assist in
making a stiff and even joint.

The plates 5 may conveniently be stamped
from sheet metal. They may if desired be
secured in place by any suitable means such 55
as set screws 8 taking into the web 9 of the
rails.

When used simply as a support or chair,
the device is applied as described, but at
suitable points between the ends of a rail, 60
instead of at the meeting ends of two rails.

I claim,

In a rail joint or support, the combination
with a rail length having a head and flat
base, of a sole plate or sleeper having up-
wardly directed members substantially fit-
ting to the rail base, and locking means
formed of a flat plate driven in with its
edges engaging respectively the underside of
the head and the angle formed between the 70
rail base and said upwardly directed
members.

In testimony whereof I affix my signa-
ture in presence of two witnesses.

LIONEL WILLIAM MACER.

Witnesses:

V. WARD,

J. A. CULLEN.
